UNITED STATES PATENT OFFICE.

GEORGE A. JOHNSON, OF CHICAGO, ILLINOIS, ASSIGNOR TO WILLIAM H. MINER, OF CHAZY, NEW YORK.

CAR-UNDERFRAME.

1,205,352.

Specification of Letters Patent. Patented Nov. 21, 1916.

Application filed October 9, 1914. Serial No. 865,787.

To all whom it may concern:

Be it known that I, GEORGE A. JOHNSON, a citizen of the United States, residing at Chicago, in the county of Cook and State 5 of Illinois, have invented a certain new and useful Improvement in Car-Underframes, of which the following is a full, clear, concise, and exact description, reference being had to the accompanying drawings, forming 10 a part of this specification.

This invention relates to improvements in car underframes.

An object of the invention is to provide an under-frame structure more particularly 15 adapted for cars employing wooden sills, which is of rigid and substantial construction, easily applied, and adapted to distribute the shocks from the draft rigging in an efficient manner to the under-frame 20 structure.

In the drawing forming a part of this specification Figure 1 is a vertical sectional view of the end portion of a railway car showing my improvements in connection 25 therewith, the section being taken substantially on the center line of the car. Fig. 2 is a horizontal sectional view taken substantially on the line 2—2 of Fig. 1 and Figs. 3 and 4 are enlarged transverse sectional views taken substantially on the lines 30 3—3 and 4—4 respectively of Fig. 1.

In the drawing 10—10 denote the wooden center sills of the car; 11 the wooden sub-sills which extend to and abut the rear side 35 of the body bolster 12; 13 the end sill; and 14 the end or dead block secured to the end sill 13. To the under side of each center sill 10, which extends to the end sill 13, there is secured a draft arm 15 which extends from 40 beneath the block 14 to the front side of the body bolster abutting latter as indicated at 16. Each draft arm 15, which may be in the form of a steel of malleable casting, is provided with a series of stops 17—17 on its 45 inner side which serve their usual function for the followers 18—18 of any well known type of draft gear, the gear shown in the drawing being of the tandem spring arrangement and employing a yoke 19 riveted 50 or otherwise suitably secured to the draw bar 20. At its front end, each draft arm 15 is provided with a depressed portion 21 which extends below the block 14 and a horizontal web 22 which extends beneath

the end sill and the corresponding center 55 sill 10. To the rear of the end sill, each draft arm is provided with an upwardly and inwardly extending shoulder or horn 23 each of which horns is provided with a face 24 bearing against the rear side of the end sill, it being apparent from an inspection of Fig. 2 that the horns 23—23 extend inwardly toward each other to points nearly in line with the center line of the gear. In this way, a large bearing is secured against 60 the rear side of the end sill whereby the shocks under draft are distributed over a larger area to the end sill. Secured to the inner and under side of each center sill 10 is an elongated angle iron 25 which extends 70 from a point considerably to the rear of the body bolster to a point approximately half way between the bolster and the end of the car. The lower horizontal web 26 of each angle iron is rigidly secured to the upper 75 horizontal flange 22 of the draft arm by means of a plurality of rivets 27 or other suitable devices. To the rear of the body bolster and extended transversely of the longitudinal sills, is a connecting plate 28 which is riveted to the horizontal webs 26 of the angle irons and fits snugly against 80 the rear side of the body bolster. Each draft arm 15, on the top thereof, is also provided with an upstanding shoulder 29 85 of box-like form which is rabbeted into the center sills 10 and against the rear side of which abuts the ends of the angle irons 25. As will be apparent from the drawings, the angle irons 25—25 are firmly united to the 90 sills 10 by means of transversely extending bolts 30—30 and vertically extending sill bolts 31—31. The draft arms 15 are furthermore connected by means of a transversely extending plate 32 at the rear thereof and just in front of the body bolster 12. Guide straps 33 are also shown detachably 95 secured to the draft arms by bolts and a saddle plate 34 as is customary.

From the preceding description, it will be 100 seen that I have provided an unusually rigid connection between the draft arm and the wooden sills, the angle irons being riveted to the draft arms and the angle irons being bolted throughout their extended length to the sills. Under buff, it is apparent 105 that the shocks are distributed through the draft arms directly to the body

bolster at the rear of the draft arm and to the center sills by means of the forward vertical sill bolts and through the intermediary of the shoulders 29 engaging the 5 ends of the angle irons 25, the shocks being also transmitted from the draft arm to the angle irons through the rivets. Under draft, the shocks are distributed to the end sill by means of the horns 23 and to the sills 10 through the vertical sill bolts and on account of the rivet connection between the draft arms and the angle irons, and in this connection it will be noted that forward movement of the angle irons is resisted not 15 only by the bolts connecting them with the sills 10 but by the transverse plate 24 which engages the rear side of the body bolster. From the preceding description it will also be seen that the under-frame construction 20 which I have provided may be readily applied, inasmuch as there is very little cutting of the sills to be done and the shocks are transmitted to the center sills to points over and to the rear of the body bolster by 25 very simple and cheap means, namely, commercially rolled angle irons.

While I have described in detail one form of my improvements, I am aware that changes and modifications may be made without departing from the spirit of the invention, and such changes and modifications are con-

templated as come within the scope of the claims appended hereto.

I claim:

1. In car underframing, the combination 35 with a wood center sill, body bolster, and end sill, of a draft arm having an integral abutment on the top thereof located between the end sill and the body bolster, and a commercially shaped iron having one web there- 40 of secured to the inner face of said center sill and having the forward end thereof in engagement with said abutment, said abutment being seated in a gain provided there- for in the center sill.

2. In under-framing for railway cars, the combination with a wood center sill, an end sill, and a body bolster, of a cast draft arm having an upper, horizontal and outwardly extending flange disposed beneath and se- 45 cured to said center sill, the draft arm ex- tending from the body bolster underneath the end sill, said draft arm having a horn near its forward end engaging the rear side of the end sill and provided also with a box-like shoulder on its upper portion, said center sill being recessed to receive said box- like shoulder.

GEORGE A. JOHNSON.
